(57) **CLAIM**

The ornamental design for a cable junction device, as shown and described.

DESCRIPTION

A portion of the disclosure of this patent document contains or may contain material which is subject to copyright protection. The copyright owner has no objection to the photocopy reproduction by anyone of the patent document in exactly the form it appears in the Patent and Trademark Office patent file or records, but otherwise reserves all copyrights whatsoever.

FIG. 1 is a front elevation view of a cable junction device.

FIG. 2 is a rear elevation view of the cable junction device.

FIG. 3 is a left side elevation view of the cable junction device.

FIG. 4 is a right side elevation view of the cable junction device.

FIG. 5 is a top view of the cable junction device.

FIG. 6 is a bottom view of the cable junction device.

FIG. 7 is a right front isometric view of the cable junction device; and,

FIG. 8 is a left rear isometric view of the cable junction device.

The broken lines shown represent unclaimed subject matter and form no part of the claimed design.

1 Claim, 8 Drawing Sheets
